(57) **CLAIM**

The ornamental design for a facial covering, as shown and described.

DESCRIPTION

FIG. 1 is a top front perspective view of a facial covering, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view thereof, shown in a used condition with a human head shown in broken lines.

The even dashed broken lines showing the inner surface edge lining in FIGS. 1, 2, 3, and 6 of the facial covering and the human head in FIG. 8 form no part of the claimed design. The dashed-dot lines represent thread stitching on the facial covering.
